DISPENSING APPARATUS

Original Filed Nov. 21, 1919

WITNESS:

E. R. Rumpf.

INVENTOR.

BY W. J. RUMP

Victor J. Evans

ATTORNEY.

Patented Nov. 27, 1923.

UNITED STATES PATENT OFFICE.

WILLIAM J. RUMP, OF SUEDBERG, PENNSYLVANIA.

DISPENSING APPARATUS.

Application filed November 21, 1919. Serial No. 339,749.

To all whom it may concern:

Be it known that I, WILLIAM J. RUMP, a citizen of the United States, residing at Suedberg, in the county of Schuylkill and State of Pennsylvania, have invented new and useful Improvements in Dispensing Apparatus, of which the following is a specification.

The object of my present sole invention is the provision of a simple, easily operated and efficient apparatus for measuring and dispensing oil and other liquids, and this without waste of liquid, without subjecting the liquid to friction, and without splashing of the liquid, and so that but little pressure will be required for the displacement of the liquid.

To the attainment of the foregoing, the invention consists in the improvement as hereinafter described and definitely claimed.

In the accompanying drawings, hereby made a part hereof:

Figure 1 is a side view illustrative of my novel apparatus complete.

Figure 2 is an enlarged detail view showing the preferred construction of the transparent measuring vessel.

Similar numerals of reference designate corresponding parts in both views of the drawings.

The apparatus is designed specifically for measuring and dispensing gasolene, and among other elements the apparatus comprises a storage tank 1 and an overflow tank 2, both of which are preferably buried in the ground at a slight distance from the ground surface, indicated by 3.

Located at a slight distance above the ground surface 3, is a measuring vessel 4, preferably, though not necessarily, of glass or other transparent material. The said vessel 4 is provided with a top 5 made removable, in order that access may be readily gained to the interior of the vessel body for cleaning purposes, and also in order to facilitate thorough cleansing of the induction end of the discharge pipe 6, which pipe 6 extends through and is removable with the said cover 5. On the upper edge of the body of the vessel 4, is a gasket 7 applied to exclude air from the interior of the vessel when the cover 5 is properly superimposed upon the vessel body. At 8 the cover 5 is provided with a valved air vent.

Each of the tanks 1 and 2 is provided with an up-take vent 9, and the bottom of the tank 2 is connected with the top of the tank 1, through the medium of a pipe 10, valved at 11. The bottom of the tank 1 is connected to the before-mentioned pipe 6 through the medium of a pipe 12; the said pipes 12 and 6 being detachably coupled at 13, and the pipe 12 being provided with an emergency cut-off 14, a spigot 15 for the drawing of small quantities of gasolene, and the cut-off 16 for use in filling the measure. At its lower end within the measure 4 and adjacent to the bottom of the latter, the pipe 6 is provided with a strainer head 17.

Connected at one end to the top of the overflow tank 2 is an overflow pipe 20, having at 21 a cut-off valve, designed to be closed while the tank 2 is being drained. Also connected to the top of the overflow tank 2 is an air pipe 22, having an air feed valve 23, and also having an arm 24, valved at 25 and designed to permit air under pressure to escape from the tank 2. The overflow pipe 20 is provided with arms 30 and 31, coupled at 32 to pipes 33 and 34 which communicate with the upper and lower portions respectively of the interior of the measure 4. The pipe 34 is valved at 35.

Connected to the top of the storage tank 1 is a pipe 40 having a valve 41, and also having an arm 42, provided at 43 with a valve to permit air under pressure to escape from the storage tank 1.

In the practical use of my novel apparatus, it is to be further noted that when it is desired to measure and dispense say, one gallon of gasolene, it is simply necessary to open the valve 16 and then fill to the mark 16^x on the measuring tank 4 as shown in Figure 1. The valve 16 is then closed and the valve 37 is opened to discharge the measuring vessel. To throw the full capacity of the measuring vessel the valves 35 and 37 are closed and the valve 16 is opened until the measuring vessel is filled to the top overflow. The valve 16 is then closed and the valve 37 is opened to discharge the measuring vessel. When the vessel 4 is supplied with more than a predetermined quantity of liquid, the valve 35 is opened prior to the opening of the valve 37 so as to throw liquid from the vessel 4 until the quantity of liquid in said vessel 4 is reduced

to the predetermined quantity desired. The valve 35 is then closed, and the valve 37 is opened for the discharge of the liquid from the vessel 4. When it is desired to drain 5 the contents of the overflow tank 2 into the storage tank 1, the valve 25 is closed, the valve 23 is opened, the valve 43 is opened, the valve 41 is closed, and the valve 11 is opened to permit liquid to pass from 10 the tank 2 to the tank 1. Then when the valve 23 is closed, valve 25 is opened, valves 11 and 43 are closed, and the valve 41 is opened, the apparatus is ready for the passage of gasolene from the storage tank to 15 the measuring vessel 4. When the storage tank 1 is to be refilled, the valve 41 is closed and the valve 43 is opened. Manifestly by virtue of the oil being drawn from the bottoms of the tanks 1 and 2, there will be 20 no accumulation of water and no liability of the said tanks being deteriorated. It will also be appreciated that in the operation of my apparatus, there is no waste and no splashing. This will be better understood 25 when it is stated that there can be no waste from the measuring vessel, inasmuch as the overflow will return to the overflow tank 2, and in this connection it will be observed that with the valve 25 open, there is a free 30 escape of air from the tank 2 so that the overflow can freely flow into said tank 2. In the refilling of gasolene or other oil or liquids, it is simply necessary to manipulate valves 16 and 35, though for the dispensing 35 of small quantities, the spigot 15 can be employed. Any means, such as a hand pump, can be used to charge the tanks with the air under pressure.

It will be understood of course that incidental to the charging of the storage tank 1 with liquid through the normally closed filling opening thereof, the valve 41 will be

closed and the valve 43 opened, and after the refilling operation, the valve 43 is closed and the valve 41 is opened.

It will be apparent from the foregoing that my novel apparatus is simple and inexpensive in construction and includes no delicate parts such as are likely to get out of order after a short period of use. It will 50 also be noted that the apparatus is compact, and that incidental to the use of the apparatus there is little danger of fire, there being nothing exposed but the filling plug of the storage tank 1.

I have illustrated the measuring vessel 4 in Figure 1 as superimposed upon a column or pedestal. This, however, is not of the essence of my invention, and it will therefore be understood that the measuring vessel 60 4 may be supported in any other approved manner without affecting my invention.

Having described my invention, what I claim and desire to secure by Letters-Patent, is:

A liquid measuring and dispensing apparatus comprising a storage tank, an overflow tank, a valved pipe connecting the bottom of the overflow tank and the top of the storage tank, an elevated measuring vessel, a 70 pipe connecting the bottom of the storage tank and the interior of the measuring vessel and having cut-offs spaced apart and a spigot located between the said spaced cut-offs, and a pipe leading upwardly 75 from the upper portion of the overflow tank and having lower and upper arms connected to the lower and upper portions, respectively, of the measuring vessel and also having a valve in the lower arm and a valve in its major portion below said lower arm.

In testimony whereof I affix my signature.
WILLIAM J. RUMP
